LIQUID LEVEL CONTROL SYSTEM

Commodore D. Ryan, Los Angeles, Calif., assignor
to Commercial Controls Corporation, a corpora-
tion of Delaware

Application October 29, 1940, Serial No. 363,258

13 Claims. (Cl. 91—43)

This invention relates to water supply systems for envelope-sealing machines, and the like, and has as a general object to simplify the construction and operation, and reduce the cost of such devices.

It is common practice in envelope-sealing machines to provide a moistening blade adapted to contact the gummed surfaces of envelopes to be sealed, and to feed water thereto through a thin slit in the blade. Such devices require a water supply system that will deliver water to the blade at a relatively exact hydrostatic head so that the water will flow through the slit in the blade in response to capillary attraction of a gummed envelope flap moving therewith, but will not force water through the slit when no envelopes are being moved therewith.

It has been common practice heretofore to regulate the hydrostatic head of the water in the moistening blades by connecting the blade to an open reservoir and to supply water to the reservoir from an inverted bottle. The neck of the bottle normally dips into the reservoir but as the water is used and the level drops below a predetermined value, it permits air to enter the bottle and displace additional water from the bottle into the reservoir.

Raising or lowering of the hydrostatic head at the moistening blade was accomplished by connecting the reservoir to the moistening blade with a flexible rubber tube, and raising or lowering the reservoir and the bottle as a unit. This was objectionable because the bottle and the reservoir were fairly heavy and a relatively sturdy and complicated mechanism was required to adjustably support them for movement vertically. Furthermore, the flexible rubber tube was undesirable since it was subject to injury and deterioration in use.

A specific object of the present invention is to eliminate the necessity of adjustably supporting the entire water reservoir and bottle and provide a simpler and mechanically more desirable way of accurately adjusting the hydrostatic head of the water in the moistening blade.

In envelope-sealing machines of the general type referred to employing a moistening blade having a slit therein, it is important that the gummed flaps of the envelope approach and leave the blade at relatively exact angles. A feature of the present invention is a particularly simple and effective envelope-flap guiding structure for controlling the path of the envelope flap past the moistening blade.

Still another object of the invention is to pro-

vide a simplified controlling mechanism for starting and stopping an envelope-sealing machine and regulating the water flow to the moistening blade of the machine.

The manner in which the foregoing objects and features are obtained will now be explained by describing a particular embodiment of the invention in detail, with reference to the drawings.

In the drawings:

Fig. 1 is a vertical section through an envelope-sealing machine incorporating a water supply system in accordance with the invention;

Fig. 2 is a detail vertical section, taken substantially in the plane II—II of Fig. 1, but showing the valve in a different position;

Fig. 3 is a detail section, similar to Fig. 2, but showing the valve in still another position;

Fig. 4 is a skeleton view, partly in section, taken substantially along the line IV—IV of Fig. 1, showing the mechanism in inactive position;

Fig. 5 is a view similar to Fig. 4, but showing the mechanism in priming position;

Fig. 6 is a detail, horizontal section, taken substantially in the plane VI—VI of Fig. 4;

Fig. 7 is a detail vertical section, taken substantially in the plane VII—VII of Fig. 1;

Fig. 8 is a detail, horizontal section, taken substantially in the plane VIII—VIII of Fig. 1;

Fig. 9 is a detail vertical section, taken in the plane IX—IX of Fig. 8; and

Fig. 10 is a detail, vertical section, taken in the plane X—X of Fig. 8.

Referring first to Fig. 1, there is disclosed a portion of an envelope-sealing machine incorporating a feed table 1 along which the bodies of envelopes are adapted to slide. This table 1 has an exposed edge 2 which separates the flaps of the envelopes from their bodies, the gummed surfaces of the envelopes moving past a moistening blade 3, which, as shown to best advantage in Fig. 9, has a central passage 4 filled with water and a narrow slit 5 in its undersurface through which the water exudes onto the gummed surfaces of the envelope flaps as they are moved therebelow. The general construction as so far described, is old; the present invention residing in details of adjustment and the method of supplying water to the passage 4 in the blade 3.

The machine includes frame elements 10, 11 and 12, which are in fixed relation to each other and support the flap-moistening mechanism. The moistening blade 3 is guidingly supported on the frame elements for lateral sliding movement

55 (with reference to Fig. 1) into and out of opera-

tive position. Thus it is secured to a supporting member 14 having a handle 15 thereon. When the blade 3 and the member 14 are moved to the left (with reference to Fig. 1) as far as they will go, they are releasably locked in this position by a latch 16 which is pivotally supported on the frame and carries at its outer end a large roller 17 which engages in a recess 18 in the handle 15. As clearly shown in Fig. 1, the latch 16 is curved and it is formed of resilient material so that it can yield sufficiently to permit the roller 17 to be moved along the handle 15 into the recess 18.

The central passage 4 in the blade 3 communicates with a passage 19 in the supporting member 14, and when the supporting member is in operating position in the machine, as shown in Fig. 1, passage 19 communicates with a passage 20 in a hollow bracket 21, which is removably supported on the frame member 11. A water-tight connection between the member 14 and the hollow bracket 21 is insured by interposing a resilient gasket 22 between the members 14 and 21, respectively.

The manner in which the bracket 21 is detachably mounted on the frame member 11 is shown in Fig. 8. Thus there is formed integrally with the bracket 21 a cross member 24 which is secured by nuts 25 to the ends of a pair of studs 26-26, the studs being screwed into the frame member 11. By simply removing the nuts 25 the bracket may be removed from the machine.

Referring now to Fig. 9, which shows the body 27 of an envelope positioned above the table 1 and the flap 28 of the envelope positioned below the moistening blade 3, it will be observed that the flap 28 is supported on each side of the moistening blade by a pair of rods 29-29, and these rods are so positioned that their upper surfaces are slightly above the level of the lowermost part of the moistening blade 3 so that the envelope flap 28 is pressed against the moistening blade as it passes thereunder. The purpose of these rods 29-29 is to provide a readily adjustable structure for supporting the envelope flaps in the proper position relative to the slit 5 in the moistening blade 3, to accurately control the amount of water to be deposited upon the gummed surface of the flap passing across the slit 5 of the sealing blade.

In accordance with the present invention, a simple and accurate adjustment of the rods 29 is provided for by eccentrically mounting these rods on the bracket 21. Thus as shown in Fig. 8, each rod 29 has a reduced end section 30 which is eccentrically disposed with respect to the axis of the rod 29, and is fitted in a mounting hole 31 in an upward extension 32 of the bracket 21. By rotating each rod 29 about its eccentric extension 30, it may be adjusted into a desired position of elevation and then locked in that position by tightening a nut 33 threaded on the free end of the extension 30.

The adjustment of the rods 29-29, as shown in Fig. 9, is set for normal operation on average envelopes, but should a greater amount of water be desired on the gummed surface of the flap, the left rod 29 may be adjusted so that the flap leaves the moistening blade at a flatter angle. If less water is required, the left rod 29 may be adjusted in the opposite direction.

The right rod 29 is adjustable for accurately regulating the tension of the envelope flap as it passes across the moistening blade slit 5.

In practice the rods 29 can be quickly adjusted for normal operation by removing the bracket 21

from the machine and setting the rods to predetermined positions by means of gauges.

The axes of the extensions 30 are parallel to the axes of the rods 29, although offset therefrom, so that regardless of the positions of adjustment of the rods 29, they always lie at the same angle relative to the moistening blade 3.

Referring to Fig. 9, each envelope is moved from left to right along the table 1, with the body of the envelope 27 on the table 1 and the flap 28 of the envelope below the table. As each envelope is initially started along the table 1, its flap extends substantially vertically downward, and means must be provided for bending the flap upwardly into the approximately horizontal position shown in Fig. 9. Of course after the flap reaches and passes above the rods 29, the latter hold the flap up against the moistening blade 3. To initially bend the envelopes upwardly, and enter them over the first rod 29, a deflecting vane 101 is provided.

As shown in Figs. 8 and 9, this vane 101 is inclined upwardly toward the upper surface of the right rod 29 and has a concave curved leading edge 102 against which the edges of the downwardly extending envelope flaps bear so that as the envelopes advance from left to right, the flaps are folded upwardly, and directed over the right rod 29, then under the moistening blade 3 and over the left rod 29. As the envelopes are fed along the table 1, they are guided in the horizontal plane, by contact of the flap edge of the envelope against a vertical guide plate 104 (Figs. 1 and 8). The vane 101 may be conveniently mounted on this guide plate 104 by providing the vane with a downwardly bent flange 105 which lies flat against the guide plate 104 and is secured thereto as by screws 106.

The rear, or trailing, edge 107 of the vane 101 extends the full length of the rods 29 to facilitate the guiding of selectively wide envelope flaps to the moistening blade 3.

As previously indicated, the bracket 21 is hollow and serves to conduct water to the moistening blade. This water is supplied from an inverted bottle 35 (Fig. 1) which bottle is supported on the left end of the bracket 21. Thus the bracket 21 has at its left end an upstanding portion 36 having a vertical passage 37, which passage is open at the top and slidably receives the lower end of a valve housing 38 secured to the neck of the bottle 35, as at 38a. This valve housing 38 defines at its upper end (as shown in Fig. 1) a valve seat 39 adapted to be closed by a valve 40 on the upper end of a valve stem 41, which is slidably supported in apertures 42 and 43 in the valve housing 38. The valve 40 is provided solely for the purpose of permitting removal and replacement of the water bottle 35, in inverted position as shown, without leaking. Thus whenever the bottle is in operative position, as shown in Fig. 1, the lower end of the valve stem 41 rests on a projection 44 in the bracket 21 which lifts the valve 40 clear of its seat 39. The valve housing 38 has apertures 45 therein, permitting free flow of water or air through the valve housings when the valve housing is in open position. The apertures 45 also permit filling of the bottle with water.

In operation the flow of water from the bottle 35 into the hollow bracket 21 is controlled by the extent to which air is admitted to the bottle to displace the water therein. Air is admitted into the bottle through the rotatable sleeve 47 of a control valve. Thus this sleeve 47 is rotatably

fitted in an open top vertical hole in the bracket member 21, offset from the neck of the bottle 35. This hole communicates at one side through a horizontal passage 49 with the passage 37 in the upstanding portion of the bracket leading into the bottle 35. The valve sleeve 47 is open at the top and has secured thereto a crankarm 50 through which it can be rotated through approximately 80°.

The sleeve 47 has a port 51 therein which is moved into and out of registration with the passage 49 in response to oscillation of the sleeve 47 by the crankarm 50. It will be observed from Fig. 3 that the port 51 has a sloping upper edge 52 which merges at its upper end into a slot or notch 53.

When the valve sleeve 47 is in one extreme position of oscillation, as shown in Fig. 1, the port 51 is completely out of registration with the passage 49 so that there is no path for the entry of air into the bottle 35 through the valve. Hence although air already in the hollow bracket 21 would flow upwardly in the bottle 35 and displace a limited amount of water down into the hollow bracket, the highest level of water in the hollow bracket would be substantially as indicated at 54, which is below the level of the lowest part of the slit in the moistening blade, the latter level being indicated at 55. Therefore, with the valve adjusted to the position shown in Fig. 1, water will not be delivered from the bottle 35 through the hollow bracket 21 and discharged from the moistening blade.

When it is desired to start operations, the valve crank 50 is rotated through substantially 80° by a mechanism to be described later, which brings the slotted portion 53 of the port 51 into registration with the passage 49, thereby providing a free path for the entry of air down through the valve sleeve and through the slot 53 and passage 49 into the bottle 35. Air enters the bottle and displaces water therefrom until the water level in the hollow bracket reaches the upper end of the slot 53, as shown in Fig. 3. As is clearly apparent from Fig. 1, the water level under these conditions is above the level of the moistening blade 3, the level of the latter being indicated by the line 57 in Figs. 2 and 3. This primes the system by quickly driving out all air from the hollow bracket and the moistening blade, some water being also discharged and collected in a catch basin 58 from which it may be carried through a suitable trough 59 to a drip pan.

In operation, the valve sleeve is left in the priming position last described and shown in Fig. 3 only for a moment. Thereafter, the sleeve is rocked back into a position such as that shown in Fig. 2, in which only a portion of the port 51 underlying the sloping edge 52 is registered with the passage 49. This prevents further entry of air into the bottle 35 until the water level in the passage 49 drops to the highest portion of the edge 52, registering with the passage 49. As the water is used up during the operation of the machine, additional air will enter as necessary to maintain the water level at the upper edge 52 of the port.

The sloping upper edge 52 of the port 51 permits a fine adjustment of the water level in the moistening blade. It will be observed from Fig. 2 that with the valve adjusted as shown therein, for normal running, the uppermost portion of the open port is very slightly above the level 57 of the moistening blade slit, so that a slight head of water is provided at the slit. With the optimum

adjustment of the water level, the hydrostatic head at the moistening blade slit is sufficient to feed water freely through the slit 5 in response to the capillary attraction of a gummed flap thereagainst, but is insufficient to cause water to leak through the slit when no envelope flaps are in contact therewith. Under certain conditions, as when sealing envelopes having very large gummed areas, it may be desirable to rotate the valve sleeve 47 into position to raise the level of the water somewhat above the level shown in Fig. 2, and insure a freer flow through the slit of the moistening blade onto the flap of the envelope.

Obviously, the length of the inclined edge 52 and the angle of this edge may be varied to provide as great a range of water level as may be necessary under the conditions of operation for which the machine is intended.

At the completion of a run of the machine, the valve sleeve 47 is again rotated into shut-off position, as shown in Fig. 1, thereby preventing leakage of water through the moistening blade.

The valve 47 is rotated through a suitable mechanism by a control handle 60, which handle also controls the starting and stopping of the power mechanism of the machine.

Thus the handle 60 is mounted on the right end of a shaft 61 which is journaled in bearings 62 and 63 in the frame members 12 and 11, respectively. There is mounted on the rear end of the shaft 61 a crankarm 64 which is connected by a pin and slot connection to the lower end of a lever 65 (Fig. 4) fulcrumed near its center by a screw 66, to the frame member 11. At its upper end, the lever 65 is pivotally connected by a screw 67 to one end of a link 68, the other end of which is slidably along a horizontal guide bar 72 which is supported on the frame member 11. Thus the link 68 may be formed of sheet metal and have a wing 69 (Fig. 6) extending forwardly over the guide 72 and then down, to form a lip 70 (Fig. 1) bearing against the front face of the guide 72. The link 68 has another, bifurcated wing 71 extending rearwardly from the wing 69 and defining a slot 73 which receives an upwardly extending crank 74 on the crankarm 50.

It will be apparent from the foregoing description that in response to oscillation of the handle 60, the crankarm 50 and the valve sleeve 47 will be oscillated.

As has been previously indicated, the handle 60 also preferably controls a switch for starting and stopping the motor that powers the sealing machine. Referring to Fig. 1, such a switch is indicated at 80, and is of the toggle type, having a bifurcated handle 81 adapted to be intercepted by a crankpin 82 on a hub member 83 pinned to the shaft 61. When the handle 60 is in "off" position (in the position shown in Fig. 7), the switch handle 81 is in clockwise position. To start the machine, the operator rocks the handle 60 clockwise through approximately 145°. During the initial portion of this movement, the pin 82 rocks the switch handle 81 counterclockwise to start the motor of the machine, after which the pin 82 leaves the slot in the bifurcated handle 81. When the machine is to be shut down, the handle 60 is rocked counterclockwise back into its original position, and during the final portion of this motion the pin 82 again engages the bifurcated handle 81 and rocks the handle into "off" position.

In the two extreme positions of the handle 60, a pointer 60a thereon abuts against stop pins 60b and 60c, respectively.

It was previously stated, in connection with the description of the valve, that when the machine is started, the valve 47 is rotated through its full range of movement to carry the slot 53 (Fig. 1) into registration with the passage 49, and then the valve is retracted to bring the valve port into running position, as shown in Fig. 2. In order to prevent the valve from being left in starting position, which would waste water, a spring mechanism is provided to automatically rock the shaft 61 away from starting position whenever the handle 60 is released. Thus referring to Fig. 1, there is mounted on the hub 83 a disc 85 cooperating with a spring detent ball 86 which is supported on a bracket 87 secured to the frame of the machine, the bracket 87 also supporting the electric switch 80. Referring to Figs. 4 and 5, the disc 85 has three detent notches 88, 89 and 90, and a straight rise 91. When the handle 60 is in "off" position, as shown in Fig. 4, the ball detent 86 is in the notch 88. The operator first rocks the handle 60 clockwise until rotation is stopped by abutment of the pointer 60a against the stop pin 60b, in which position the rise 91 on disc 85 depresses the ball detent 86. The parts are then in the position shown in Fig. 5, and the ball detent 86 is constantly exerting a force tending to reverse the handle 60. If the operator then releases the handle, the detent will reverse the disc 85 and the shaft 61 sufficiently to carry the slot 53 (Fig. 1) of the valve sleeve 55 clear of the passage 49, but with the highest portion of the sloping edge 52 in registration with the passage 49, thereby providing the maximum working flow of water. If a smaller flow is desired, the operator rocks the handle 60 back to bring either the notch 90 or the notch 89 into engagement with the ball detent 86. In ordinary practice, three positions of adjustment involving the notches 89, 90 and the straight rise 91 provide a sufficient latitude of adjustment. Obviously, however, if desired, a larger amount of smaller detent notches could be provided, to give a finer adjustment.

Summarizing the operation of the machine, clockwise movement of the handle 60 from the "off" position shown in Fig. 4 into priming position shown in Fig. 5, actuates the switch 81 to start the motor of the machine and floods the moistening blade to eliminate all air therefrom and insure immediate operation thereof. Thereafter release of the handle 60 permits it to automatically be retracted by the straight cam surface 91 and the ball detent 86 into working position of maximum flow. Further manual retraction of the handle to bring one of the notches 90 or 89 into engagement with the ball detent 86 reduces the flow of water to the moistening blades. During the adjusting movements of the handle 60 to regulate the flow of water, the pin 82 is beyond the point of contact with the bifurcated switch handle 81 and does not affect the switch. When the machine is to be shut down, the handle is simply rocked back into starting position, as shown in Fig. 4, which returns the switch handle 81 to "off" position, as shown in Fig. 7, and completely closes the valve sleeve 47.

Although for the purpose of explaining the invention a specific embodiment thereof has been described in substantial detail, it is to be understood that various changes may be made in the particular construction shown without departing from the invention, which is to be limited only to the extent set forth in the appended claims.

I claim:

1. In an envelope-sealing machine, a rotatable control member and means for rotating it between first and second extreme positions, said sealing machine including envelope flap-moistening means and means for supplying water thereto, means for varying the hydrostatic head of the water supplied, between extreme values in response to rotation of said control member, and means for controlling the movement of said control member, comprising a cam element and a spring detent element, one of said elements being secured to said control member for rotation therewith and the other element being anchored in stationary position, said cam element having a rising cam surface for compressing said spring detent in response to movement of said control member into its full "on" position, whereby the detent partially retracts the control member when the latter is released from manual control, said means for varying the hydrostatic head of said water supply increasing said head to an excessive value to prime said moistening system while, and only while, said control member is in said extreme position.
2. Apparatus as described in claim 1, in which said cam member has a plurality of detent recesses therein for yieldably engaging said detent and yieldably retaining said control member in one of a plurality of predetermined positions within its range of movement.
3. In apparatus of the character described, in combination, means for supplying liquid at a variable hydrostatic head including a fixed conduit, a container positioned above a portion of said conduit and connected thereto whereby liquid can flow from said container into the conduit in response to admission of atmospheric air to said container, valve means including an open top chamber having a port in the side thereof of communicating with said conduit at a point below said container, and means for varying the height of the upper edge of said port, whereby air enters said container through said valve means to displace liquid from said container into said conduit until the liquid level in the conduit rises to the level of the upper edge of said port.
4. In apparatus for controlling the flow of liquid to a moistening device having an orifice, in combination, a liquid container, means forming a conduit connected to said container and said device for conducting liquid from said container to said device, means for restricting the flow of liquid from said container to maintain the liquid level in said moistening device below the orifice therein when said device is out of use, and means for selectively adjusting said restricting means to raise said liquid level to any one of a plurality of positions above said orifice.
5. In apparatus for controlling the flow of liquid to a moistening device having an orifice, in combination, a liquid container, means forming a conduit connected to said container and said device for conducting liquid from said container to said device, means for restricting the flow of liquid from said container to maintain the liquid level in said moistening device below the orifice therein when said device is out of use, and means for selectively adjusting said restricting means to raise said liquid level to any one of a plurality of positions above said orifice, said restricting means including a pair of relatively adjustable port defining members movable between open and closed positions to meter into said

container a predetermined amount of air and thereby selectively adjust the liquid level with relation to said orifice.

6. In apparatus for controlling the flow of liquid to a moistening device adapted to be installed in a power-operated envelope sealing machine or the like having a manually operable starting lever, wherein the envelopes are fed automatically to the moistening device, said moistening device having an orifice, the combination of, a liquid container, a conduit connected to said container and to said moistening device for leading liquid from the former to the latter, and means responsive to operation of said starting lever to operate said machine for varying the hydrostatic head of the liquid in relation to the level of said orifice, said means including a valve associated with said conduit and operable to connect said conduit with the atmosphere to meter air into said container.

7. In apparatus for controlling the flow of liquid to a moistening device adapted to be installed in a power-operated envelope sealing machine or the like, wherein the envelopes are fed automatically to the moistening device, said moistening device having a downwardly facing orifice, the combination of, a conduit having its outlet end connected to said moistening device, a liquid container mounted on and supported by the inlet end of said conduit, and a valve in said conduit operable to meter atmospheric air into said container to vary the hydrostatic head of liquid in said moistening device relative to said orifice.

8. In apparatus for controlling the flow of liquid to a moistening device adapted to be installed in a power-operated envelope sealing machine or the like having a manually operable starting lever, wherein the envelopes are fed automatically to the moistening device, said moistening device having a downwardly facing orifice, the combination of, a conduit having its outlet end connected to said moistening device, a liquid container mounted on and supported by the inlet end of said conduit, a valve in said conduit operable to meter atmospheric air into said container to vary the hydrostatic head of liquid in said moistening device relative to said orifice, and means connected to said valve and responsive to operation of said starting lever to initiate operation of said machine to connect said conduit with the atmosphere for raising the hydrostatic head of liquid in said moistening device relative to said orifice.

9. As an article of manufacture, a liquid conduit for conducting liquid from a container to a moistening device, said conduit comprising an elongated rigid pipe the outlet end of which is adapted to be connected to said moistening device, means forming a liquid inlet chamber at the other end of said pipe adapted to be connected to said container, means forming an air inlet chamber on said pipe, means in said air inlet

chamber for cutting off communication between said pipe and the atmosphere, said liquid and air inlet chambers being disposed adjacent one another, means forming a port between said chambers, and a rotary valve operatively mounted in one of said chambers for varying the vertical dimension of said port.

10. In apparatus of the character described, in combination, a support, a moistening device detachably mounted on said support, a rigid liquid conduit rigidly mounted on said support, means forming a separable liquid-tight connection between said device and the outlet end of said conduit, a liquid container detachably mounted on and supported by the inlet end of said conduit, and valve means on said conduit for metering air into said container for variably controlling the hydrostatic head of the liquid in said moistening device.

11. In apparatus of the character described, in combination, means for supplying liquid at a variable hydrostatic head including a fixed conduit, a container positioned above a portion of said conduit and connected thereto whereby liquid can flow from said container into the conduit in response to admission of atmospheric air to said container, valve means including an open top chamber having a port in the side thereof communicating with said conduit at a point below said container, means for varying the height of the upper edge of said port, whereby air enters said container through said valve means to displace liquid from said container into said conduit until the liquid level in the conduit rises to the level of the upper edge of said port, said height varying means including a cylindrical sleeve fitted in said chamber and having a port adapted to be variably registered with the port in said cylinder, and means for rotating said valve sleeve.

12. Apparatus as described in claim 11 in which at least one of said two ports has a sloping upper edge, whereby the height of the passage defined by the two said ports when the valve is in partially open position is determined by the height of that portion of said sloping edge of the one port which is in registration with the other port.

13. In apparatus of the character described, in combination, a support, a moistening device detachably mounted on said support, a rigid liquid conduit rigidly mounted on said support, means forming a separable liquid-tight connection between said device and the outlet end of said conduit, a liquid container detachably mounted on and supported by the inlet end of said conduit, and valve means supported by said conduit and disposed between said moistening device and said liquid container and forming communication between the atmosphere and said liquid container for controlling the hydrostatic head of the liquid in said moistening device.

COMMODORE D. RYAN.
